UNITED STATES PATENT OFFICE.

LOUIS A. FALK, OF CHICAGO, ILLINOIS, ASSIGNOR OF ONE-HALF TO
GEORGE A. SCHMIDT, OF CHICAGO, ILLINOIS.

LIQUID-SOAP DISPENSER.

No. 840,925.

Specification of Letters Patent.

Patented Jan. 8, 1907.

Application filed March 8, 1906. Serial No. 304,925.

To all whom it may concern:

Be it known that I, LOUIS A. FALK, a citizen of the United States, residing at Chicago, in the county of Cook and State of Illinois, have invented certain new and useful Improvements in Liquid-Soap Dispensers; and I do hereby declare the following to be a full, clear, and exact description of the invention, such as will enable others skilled in the art to which it appertains to make and use the same.

My invention relates to a novel construction in a valve for liquid-soap-dispensing apparatus, the object being to provide a simple and efficient device of this character which will operate to discharge at each operation a measured quantity of said soap; and it consists in the features of construction and combinations of parts hereinafter fully described and claimed.

In the accompanying drawings, illustrating my invention, Figure 1 is a central vertical section of a valve constructed in accordance with my invention disposed upon the lower end of a receptacle adapted to contain liquid soap. Fig. 2 is a plan section of the same, on an enlarged scale, on the line 2 2 of Fig. 1. Fig. 3 is a plan view, on an enlarged scale, of the upper end of the piston.

As before stated, my invention has for its object to provide a simple and efficient valve for the purpose specified which is positive in operation and will cause a measured quantity of liquid to be discharged at each operation. To this end my said valve consists practically of a miniature force-pump connected at its inlet end with the source of supply of liquid soap and the discharge end of which terminates in a discharge-nozzle rigidly connected with the piston of the pump whereby the latter is actuated.

I am aware that the force-pump principle has been heretofore embodied in a device of this character; but so far as I am informed such embodiment differs materially in many respects from my present invention, in which all operating parts are disposed so as to occupy the least possible space and afford the greatest simplicity of construction and operation and relatively the least liability to disorder and breakage.

My said device comprises the cylinder A, which is open at one end and at said end is provided with an annular flange B, which is

internally threaded to receive the threaded neck of the receptacle C for liquid soap. At its other end said cylinder is provided with an integral annular flange E, forming a sleeve in the hollow piston-rod F is telescopically and revolvably movable. The said hollow piston-rod F is integral with the piston G, disposed in said cylinder A and which carries the inlet and exhaust valves H and I. The said inlet-valve H is a mushroom valve adapted to seat on the valve-seat J, disposed in the inner face of said piston, around an opening or port K through the latter, the said valve H being provided; preferably, with an X-shaped (in cross-section) stem, the longitudinal recesses in said stem constituting passages for the liquid soap. The said valve H is normally held on its seat by means of a spring, as will be hereinafter described. The said piston-rod F, as before stated, is hollow, and the central opening therein is extended into the piston G, terminating below the upper face of the latter. In the said upper face an opening L is bored, which intersects the central opening in said piston and cuts the wall thereof at one side to provide a longitudinal slot M, through which communication is established between said central opening and said opening L, the latter forming the valve-chamber in which the exhaust or delivery valve I is disposed. In the bottom of said valve-chamber L is a valve-seat O, which is concentric with said chamber and with a small opening N in the bottom thereof. The said valve I consists, preferably, of a ball which seats by gravity. The said valve-chamber L is closed at the upper end by means of the screw-plug P, the head of which is annularly enlarged and adapted to enter the enlarged upper end of said chamber L. The latter is preferably disposed diametrically opposite the opening K, through which the stem of the inlet-valve H passes, and extending diametrically across said piston in its upper face is a groove Q, disposed in alignment with the center of said valve-chamber L and said port K. In said groove a straight wire spring R is disposed, which is provided at one end with a loop adapted to receive the shank of said screw-plug P and be clamped between the head of the same and the annular shoulder formed by the annular enlargement of the upper end of said valve-chamber L. The free end of said spring R passes through an opening in the upper end

of the stem of said valve H, and it will be noted that by means of this arrangement the opening movement of said valve is limited by said spring. An annular flange S is disposed 5 on the outer edge of said head D, concentric with the sleeve E, but of less length. Fitting telescopically at its upper end within said flange S is a nozzle T, provided at its lower end with an inwardly-extending threaded 10 annular flange U, adapted to receive the externally-threaded lower end of said piston-rod F and held securely in place on the latter by means of the lock-nut V. Disposed in the annular chamber between the upper end 15 portion of said nozzle and said sleeve E and piston-rod F is a spiral compression-spring W, bearing at one end on said cylinder-head D and at its other end on said flange U and serving to normally hold said piston at the 20 lower limit of its movement. The mouth portion of said nozzle T is preferably annularly enlarged and flaring and is provided with suitable means for the admission and discharge of air, such as the openings Y 25 therein.

My said device operates as follows: The receptacle carrying my device is suitably supported on or adjacent the washstand and the person desiring to wash places the 30 palm of his or her hand over the mouth of the nozzle T and forces the latter upwardly against the action of said spring W. This action forces said piston upwardly and obviously forms a partial vacuum in the annular 35 chamber formed between the cylinder-head and piston and around the piston-rod, which fills as rapidly as the said piston rises, the inlet-valve H being opened against the action of the spring R by fluid-pressure exerted 40 thereon during its opening movement and said exhaust or discharge valve I being maintained closed by the same means and its own gravity. The said nozzle is immediately released, and the spring W then returns 45 the same to its normal position, the piston during this movement exerting pressure on the liquid contents of the pump-chamber, which serves to force the said valve I off its seat and causes such liquid to enter said 50 valve-chamber L and pass thence through said slot M and through said piston-rod F into the palm of the operator's hand. During the downward movement of said piston the valve H will obviously be maintained 55 closed by the spring R and by the fluid-pressure exerted thereon. It will be noted that the pump-chamber is normally entirely filled by said piston and all liquid and air exhausted therefrom at each operation. I be- 60 lieve that this is very advantageous in enabling me to secure a higher vacuum than would otherwise be obtainable, and hence renders the operation of the device more positive. A thin film of soap would always re- 65 main in said chamber, and this might cause

the valve H to stick to the cylinder-head. To prevent this, the opening movement of said valve is limited by its actuating-spring R, as before described. I desire also to direct particular attention to the fact that the 70 piston and all parts connected therewith are freely revoluble, so that a misguided operator can do no harm by revolving the nozzle instead of pressing the same upwardly. The upward movement of said piston is limited 75 by contact of the upper end of the nozzle T with the cylinder-head or by contact of the flange U with the lower end of said sleeve E.

My said device is simple, compact, has relatively few parts, and is readily assembled 80 and taken apart for purposes of repair.

I claim as my invention—

1. A device of the kind specified, comprising a pump-cylinder open at one end and provided at its other end with a head having 85 a central opening, a piston reciprocally movable in said cylinder and provided with a hollow piston-rod passing through said opening in said head, a valve-chamber in said piston communicating with said piston-rod and 90 with the pump-chamber, a valve disposed in said chamber for normally shutting off communication with said pump-chamber, an opening in said piston establishing communication between said pump-chamber and a 95 source of supply of liquid connected with said open end of said cylinder, a spring-pressed valve controlling said port at its pump-chamber end, and a spring disposed in operative relation to said piston to maintain 100 the same normally in contact with said cylinder-head.

2. A device of the kind specified, comprising a pump-cylinder communicating at one end with a source of supply of liquid, a head 105 on the other end of said cylinder provided with a central opening, a piston disposed in said cylinder, a hollow piston-rod connected therewith and passing through said opening in said head, a valve-controlled outlet-port 110 therein communicating at its delivery end with said piston-rod, and a spring disposed in operative relation to said piston to maintain the same normally at one limit of its movement.

3. A device of the kind specified, comprising a pump-cylinder communicating at one end with a source of supply of liquid, a head on the other end of said cylinder provided with a central opening, a piston disposed in 120 said cylinder, a hollow piston-rod connected therewith and passing through said opening in said head, an inlet-port in said piston, a valve controlling the same on the pressure side of said piston, a stem on said valve passing through said port, a bar-spring engaging said free end of said valve-stem and at its free end spanning the said inlet-port to limit the opening movement of said valve, a valve-controlled outlet-port in said piston com- 125

municating at its delivery end with said hollow piston-rod, and a spring disposed in operative relation to said piston to maintain the same normally at one limit of its movement.

4. A device of the kind specified, comprising a pump-cylinder communicating at one end with a source of supply of liquid, a head on the other end of said cylinder provided with a central opening, a piston disposed in said cylinder, a hollow piston-rod connected therewith and passing through said central opening in said cylinder-head, a valve-controlled inlet-port in said piston, a valve-controlled discharge-port communicating at its delivery end with said piston-rod, a removable nozzle disposed on the free end of said piston-rod, and a spring interposed between said nozzle and said cylinder-head adapted to maintain said piston normally at one limit of its movement.

5. A device of the kind specified, comprising a pump-cylinder open at one end and communicating at said end with a source of supply of liquid, a head on the other end of said cylinder having a central opening, an

annular flange surrounding said opening and constituting a hollow stem, a piston disposed in said cylinder, a hollow piston-rod connected therewith and passing through said hollow stem, a valve-controlled inlet-port in said piston, a valve-controlled discharge-port communicating with said hollow piston-rod, an annular flange on the other edge of the head end of said cylinder disposed parallel with said hollow stem, a nozzle secured to the free end of said piston-rod, an annular flange on said nozzle projecting at its free end into the annular space between said last-named flange and said hollow stem, and a spring disposed within said flange on said nozzle and bearing on the latter and said cylinder-head to maintain said piston normally at one limit of its movement.

In testimony whereof I have signed my name in presence of two subscribing witnesses.
